APPARATUS FOR FILTERING AND AGITATING PLATING SOLUTIONS

Stanley S. Cady, St. Paul, and Winston E. Sabatka, Minneapolis, Minn.

Application November 21, 1951, Serial No. 257,477

8 Claims. (Cl. 210—151)

1

The invention herein presents an apparatus for filtering and agitating plating solutions.

The apparatus of the invention comprises a container to be situated in a tank for plating solution. The container is constituted as hollow exterior and interior cylindrical elements providing an annular chamber therebetween. A pump cylinder below the hollow interior cylindrical element houses pump plungers propelled by a drive shaft. Outlets from the pump cylinder are open to the annular chamber. A hollow cylindrical filtering element divides said annular chamber into external and internal annular compartments. A horizontal wall separates the lower end of the hollow interior cylindrical element from the pump cylinder, save for an inlet through said horizontal wall, and a horizontal partition within said hollow interior cylindrical element, above said horizontal wall, separates an upper portion of a concavity provided by the hollow interior cylindrical element from a lower portion of said concavity contiguous with the horizontal wall, save for an opening through said horizontal partition. A floating cylinder controls flow of plating solution to the concavity of the hollow interior cylindrical element. There is means for feeding plating solution from the bottom of the tank by way of the concavity in said hollow interior cylindrical element to the pump cylinder to be forced through the plating solution. Means also is included for backwashing the filtering element thus to cause it to be cleaned. With the floating cylinder at a relatively low elevation and the pump pistons in operation, plating solution will flow into the pump cylinder from the tank and be forced through the filtering element back into an upper portion of said tank. With the floating cylinder at a comparatively high elevation, plating solution can be drawn from the bottom of the tank into the pump cylinder and forced to the top of said tank, as, for example, to circulate diatomaceous earth throughout the plating solution.

In the accompanying drawings forming a part of this specification,

Fig. 1 is a perspective view, partially in section and partially broken away, of an apparatus made according to the invention;

Fig. 2 is an enlarged central vertical sectional view of the apparatus;

Fig. 3 is a fragmentary view corresponding generally with the disclosure of Fig. 2 but showing a floating cylinder of the apparatus in a different position;

Fig. 4 is a side elevational view, partially in section and partially broken away, on the scale of Fig. 2, of the apparatus, disclosing parts additional to those shown in Figs. 1 and 2; and

Fig. 5 is a side elevational view, on a reduced scale, disclosing the apparatus as when sup-

2

ported within a tank containing plating solution to be filtered and agitated.

A rigid container 9 of the apparatus includes a relatively long, hollow exterior cylindrical element 10 and a relatively short, hollow interior cylindrical element 11 within and in spaced, concentric relation to said hollow exterior cylindrical element. The hollow interior cylindrical element 11 is at the elevation of a lower portion of the hollow exterior cylindrical element 10, the lower ends of said hollow interior and exterior cylindrical elements terminate in a single plane, and an annular chamber 12 between and bounded by the hollow interior and exterior cylindrical elements and at elevation below the upper end of the hollow exterior cylindrical element. The lower ends 15 of the hollow interior and exterior cylindrical elements, as well as the lower end of the annular chamber 12, are closed by a base member 14 of flat material, constituting a bottom wall of the container, removably secured, as at 15, to flanges 20 on the lower end of the hollow exterior cylindrical element 10 and up against the lower end 17 of the hollow interior cylindrical element 11.

A horizontal annular wall 18, in the lower end portion of the hollow interior cylindrical element 11 and spaced relation to the base wall 14, constitutes the upper wall of a pump cylinder 19 bounded at its lower side by said base wall and at its periphery by the lower portion of the hollow interior cylindrical element 11. An inlet 20 to the pump cylinder 19 is bounded by the inner marginal edge of said horizontal annular wall 18, outlets 21 from said pump cylinder to the annular chamber 12 are constituted as perforations in said hollow interior cylindrical element, and except for the inlet 20 and the outlets 21 the pump cylinder 19 is closed.

A horizontal partition 22 within the hollow interior cylindrical element 11 separates an intermediate portion 23 of a concavity bounded by 45 said hollow interior cylindrical element, above the horizontal annular wall 18 and contiguous with the inlet 20, from an upper portion of said concavity, above the horizontal partition, save for an opening 24 through said horizontal partition bounded by an upwardly facing, conical surface 25.

A drive shaft 26 extending axially through the container 9 has an intermediate portion thereof rotatably mounted, as at 27, in the horizontal partition 22 and a lower portion thereof rotatably mounted, as at 28, in the base member or wall 14. Spaced pistons 29, fixedly secured to the drive shaft 26, as at 30, and extending radially therefrom, are situated within the pump cylinder 19. The construction and arrangement will be such

that in response to rotation of the drive shaft 26, plating solution, indicated 31, will be drawn by the pistons 29 through the inlet 20 from the intermediate portion 23 of the concavity bounded by the hollow interior cylindrical element 11 into the pump cylinder 19 and forced by said pistons through the outlets 21 into the annular chamber 12.

The annular chamber 12 is divided into external and internal annular compartments, denoted 32 and 33, respectively, by a hollow cylindrical filtering element 34 in spaced, concentric relation to both the internal surface of the exterior cylindrical element 10 and the external surface of the interior cylindrical element 11. The opposite ends of the hollow cylindrical filtering element 34 are fitted and snugly seated in circular grooves, represented 35 and 36, respectively, in the annular wall 13 and the base wall 14. Said base wall 14 is removable in order that filtering elements such as 34 may be readily removed and replaced.

An upper portion of the exterior cylindrical element 10 integrally supports an outwardly extending, first tubular element 37 in perpendicular relation to the container 9, and said first tubular element in turn integrally supports a second tubular element 38 in parallel relation to said container and extending to position both above and below the first tubular element 37. The second tubular element 38 rotatably supports a pipe 39 fitted to said second tubular element in fluid-tight manner and against longitudinal movement. A lower end portion 40 of the pipe 39 extends to position below the second tubular element 38, and an upper portion 41 of said pipe extends to position above said second tubular element. Manually operable valves assembled with the upper end portion 41 of the pipe 39 are designated 42 and 43, respectively, and an outlet connection from the valve 42 is indicated 44. An oblique partition 45 across the pipe 39, at the elevation of the first tubular element 37 and an intermediate portion of the second tubular element 38, separates the lower and upper end portions 40 and 41 of the pipe 39 from each other. Said pipe is adapted to be turned to position as in Fig. 2 to afford communication between the external annular chamber 32 and the interior of the lower end portion 40 of the pipe, by way of a passage 46 through the first tubular element 37 and a port 47 in a part of said pipe below the oblique partition 45, while shutting off communication between said exterior annular chamber and the interior of the upper end portion 41 of the pipe, or to position as in Fig. 4 to afford communication between said external annular chamber 32 and the interior of the upper end portion 41 of said pipe, by way of said passage 46 and a port 48 in a part of the pipe above the oblique partition 45, while shutting off communication between the exterior annular chamber and the interior of the lower end portion 40 of said pipe.

The drive shaft 26 can be rotated in any manner which may be preferred. As disclosed, a pulley 49 upon said drive shaft, above the container 9, is for accomplishing its rotation. Agitating propellers upon the drive shaft, below the container 9, are denoted 50.

When the apparatus is applied to use, the container 9, with appurtenances, will be situated in a tank, such as 51, containing plating solution 31. Means for supporting said container 9 for vertical adjustment in plating solution in said

tank is as shown constituted as an L-member 52 having its longer vertical arm secured, as at 53, to the exterior cylindrical element 10 and its shorter horizontal arm secured, as at 54, upon an upright 55, fixedly supported by the tank, for adjustment longitudinally of said upright.

A floating cylinder of the apparatus is constituted as a hollow cylindrical member 56 snugly fitted into and vertically slidably in the upper end portion of the exterior cylindrical element 10, and a hollow annular member 57 integral or rigid with an interior, lower portion of said hollow cylindrical member 56. The construction and arrangement will be such that with increase of depth of plating solution in the upper portion of the container 9 the floating cylinder will be elevated to cause its hollow cylindrical member to project to increasing extent above the upper end of the exterior cylindrical element 10, and with decrease of depth of plating solution in the upper portion of said container said floating cylinder will become depressed to cause its hollow cylindrical member to project to decreasing extent above the upper end of said exterior cylindrical element.

The opening 24 through the horizontal partition 22 is for removably containing one end portion 58 of an intake pipe 59 while the other end portion 60 of said intake pipe is situated at or near the bottom of the tank 51. As shown, the end portion 58 of the intake pipe 59 includes a downwardly facing conical part 61 to be snugly fitted to and down against the upwardly facing conical surface 25 bounding said opening 24. See Figs. 2 and 4.

The apparatus is capable of employment to perform several useful services.

As shown in Fig. 2 of the drawings, where the floating cylinder is at elevation to situate the upper end of the hollow cylindrical member 56 of said floating cylinder below the surface of plating solution, as in a tank such as 51, when the drive shaft 26 is set in operation, thus to actuate the pump pistons 29, plating solution will be forced from the pump cylinder 19 into the interior annular compartment 33, through the filtering element 34 into the exterior annular compartment 32, and through the passage 46, the port 47 and the lower end portion 48 of the pipe 39 into said tank, while at the same time plating solution is running, or being skimmed, from an upper level of plating solution in said tank into the container 9 and said pump cylinder 19. This is, when the apparatus is situated as in Fig. 2 and the pump is in operation, plating solution will be skimmed off of the surface of plating solution, flow by gravity to the pump cylinder, and be pumped through the filtering element 34 and back into the tank by way of the lower end portion 48 of the pipe 39. The agitating propellers 50 will be operative all of the time while the pump is in operation. Skimming off the surface of plating solution is a desirable operation because it causes surface impurities to be removed. Agitation makes for tendency toward faster plating.

As shown in Figs. 4 and 5, where the intake pipe 59 is in place, when the drive shaft 26 is set in operation to actuate the pump pistons 29, with the upper portion of the container 9 and the floating cylinder situated above the filtering solution level, as in Fig. 5, plating solution will be drawn or sucked from the tank 51 through said intake pipe 59 into the pump cylinder 19, and forced from said pump cylinder into the in-

terior annular compartment 33, through the filtering element 34 into the exterior annular chamber 32, and through the passage 46, the port 48 and the upper end portion 41 of the pipe 39 by way of the valve 42 and the outlet connection 44 back into the tank 51.

When parts of the apparatus are situated as in Figs. 4 and 5, with the intake pipe 59 removed, as in Fig. 2, and the drive shaft 26 is set in operation to actuate the pump pistons 29, there can be circulation of plating solution in a continuous system including the filtering element and the pump cylinder as part thereof. This is, plating solution will be forced from said pump cylinder into the interior annular compartment 33, through the filtering element 34 into the exterior annular compartment 32, and through the passage 46, the port 48 and the upper end portion 41 of the pipe 39 by way of the valve 42 and the outlet connection 44 to the container 9 and the pump cylinder by way of the opening 24. Such circulation desirably will be established immediately after loose or porous diatomaceous earth, intended to enhance the quality of the filtering element, has been added to the container 9. Stated otherwise, circulation of plating solution containing diatomaceous earth through the filtering element 34, in the manner as set forth, will render said filtering element capable of more efficiently performing its intended service than otherwise would be the case.

The filtering element 34 can be cleaned by backwashing, with the parts situated as in Figs. 4 and 5 and the pump inoperative, in response to reverse flow through the upper end portion 41 of the pipe 39 accomplished by opening the valve 43, to allow flow of water under pressure from a source (not shown), and closing the valve 42. That is to say, supposing the upper end portion 41 of the pipe 39 to be connected with a source of water under pressure controlled by the valve 43, said valve could be opened to establish forced flow reversely through said pipe, the passage 46, the filtering element 34 and the pump cylinder.

A drain plug in the base member or wall 14 is represented 62. Of course, the drain plug 62 will be removed, and the apparatus will be free of plating solution when backwashing of the filtering element 34 is accomplished.

What is claimed is:

1. In an apparatus for filtering plating solutions, a hollow exterior element, a hollow interior element within and in spaced relation to said hollow exterior element and providing therewith an annular chamber, a wall extending between portions of said hollow exterior and interior elements and closing an upper end of said annular chamber, a base member closing a lower end of said annular chamber and lower ends of said hollow exterior and interior elements, a pump cylinder within a lower portion of said hollow interior element, an inlet to said pump cylinder, an outlet from the pump cylinder to said annular chamber, a pump plunger in said pump cylinder, means for actuating said pump plunger, a hollow filtering element in said annular chamber in spaced relation to said hollow exterior and interior elements and having its opposite ends contiguous with said wall and said base member, respectively, an outlet from said hollow exterior element, a hollow interior member snugly fitted into and vertically slideable in an upper portion of said hollow exterior element, and a float member rigid with an interior lower portion of said hollow interior member.

2. The combination as specified in claim 1 wherein said base member is detachably assembled with said hollow exterior and interior elements and said hollow filtering element is removably situated in said annular chamber.

3. The combination as specified in claim 1, and a partition wall within said hollow interior element in spaced relation to said pump cylinder, said partition wall being provided with an opening for snugly receiving a pipe connection.

4. The combination as specified in claim 1, and an agitator rigid with said means for actuating said pump plunger and situated below said base member.

5. In an apparatus for filtering plating solutions, a hollow exterior element, a hollow interior element within and in spaced relation to said hollow exterior element and providing therewith an annular chamber, a wall extending between portions of said hollow exterior and interior elements and closing an upper end of said annular chamber, a base member closing a lower end of said hollow exterior and interior elements, a pump cylinder within a lower portion of said hollow interior element, an inlet to said pump cylinder, an outlet from the pump cylinder to said annular chamber, a pump plunger in said pump cylinder, means for actuating said pump plunger, a hollow filtering element in said annular chamber in spaced relation to said hollow exterior and interior elements and having its opposite ends contiguous with said wall and base member, respectively, an outlet from said hollow exterior element, a tubular element supported by said hollow exterior element, a pipe rotatably fitted to the tubular element and having portions extending both upwardly and downwardly from said tubular element, an oblique partition across said pipe at the elevation of said outlet from said hollow exterior element and separating said upwardly and downwardly extending portions of the pipe from each other, said pipe having a first port therein below the oblique partition and a second port therein above said oblique partition adapted to be selectively aligned with said outlet from said hollow exterior element.

6. The combination as specified in claim 5, an outlet connection from said upwardly extending portion of said pipe, and a manually operable valve for controlling said outlet connection.

7. The combination as specified in claim 5, an inlet connection to said upwardly extending portion of said pipe, and a manually operable valve for controlling said inlet connection.

8. The combination as specified in claim 5, an outlet connection from said upwardly extending portion of said pipe, a manually operable valve for controlling said outlet connection, an inlet connection to said upwardly extending portion of said pipe, and a manually operable valve for controlling said inlet connection.
